A flotation separation system for partitioning a slurry comprises a flotation separation cell that comprises a sparger unit and a separation tank. The sparger unit comprises a slurry inlet for receiving a slurry and a gas inlet for introducing a gas into the slurry. The sparging mechanism disperses the gas bubbles within the slurry. A high shear element comprising a rotating shaft and a rotating high shear element mounted to it located within the sparging mechanism shears the gas into a bubble dispersion within the slurry. A slurry outlet discharges the slurry containing the bubble dispersion into the separation tank. An adjustable distributor plate at the slurry outlet restricts the flow of slurry through the slurry outlet. The distributor plate is mounted to the rotating shaft and rotates with the high shear element.

FLOTATION SEPARATION DEVICE

This application is a continuation in part of U.S. non-provisional patent application Ser. No. 14/587,173 which will issue as U.S. Pat. No. 10,478,830 filed on Dec. 31, 2014 which in turn is a continuation of U.S. Pat. No. 8,960,443 filed on Apr. 11, 2008, which is incorporated herein by reference.

BACKGROUND

Flotation separators are used extensively throughout the minerals industry to partition and recover the constituent species within slurries. A slurry is a mixture of liquids (usually water) with various species having varying degrees of hydrophobicity. The species could be insoluble particulate matter such as coal and various other minerals or liquid/liquid systems such as oil in water. Flotation separators work on the principle that the various species within the slurry interact differently with bubbles formed in the slurry. Gas bubbles introduced into the slurry attach, through a combination of physical and chemical means, to one or more of the hydrophobic species of the slurry. The bubble-hydrophobic species agglomerates are sufficiently buoyant to lift away from the remaining constituents and are removed from the top of the separation system for further processing. Various methods used to achieve this process typically require significant energy to inject gas into the slurry, form a bubble dispersion, and maintain the particulates in suspension.

SUMMARY

What is claimed is a flotation separation system for partitioning a slurry. The slurry includes a hydrophobic species that can adhere to gas bubbles that are formed within the slurry. The flotation separation system includes a flotation separation cell. The flotation separation cell has a sparger unit and a separation tank. The separation tank is constructed to allow the bubble dispersion to predominantly concentrate in the top of the separation tank. The separation tank is either open to atmosphere or closed at a pressure other than atmospheric.

The sparger unit includes a slurry inlet, a slurry outlet, a sparging mechanism, a high shear element, and a gas inlet. The slurry inlet is located at a first portion of a sparging mechanism and is for receiving a slurry. The gas inlet is also located at the first portion of the sparging mechanism and is for introducing a gas into the slurry. The gas itself has enough pressure to introduce gas into the slurry.

The sparging mechanism is for dispersing the gas bubbles within the slurry. The effective open area within the sparging mechanism is substantially the same as the effective open area in the sparger unit that is both upstream and downstream from the sparging mechanism. The sparging mechanism is also constructed such that the slurry flows through the sparging mechanism in a substantially unrestricted manner. Furthermore, the pressure across the sparging mechanism is about 10 psig or less, during operation of the flotation separation system.

A high shear element is located within the sparging mechanism, between the first portion and a second portion of the sparging mechanism. This high shear element shears the gas into a bubble dispersion within the slurry for adhesion of the hydrophobic species to the bubble dispersion within the sparger unit. The high shear element comprises a rotating shaft and a rotating high shear element mounted to the rotating shaft. A slurry outlet is located at the second

2

portion of the sparging mechanism. The slurry outlet is for discharging the slurry containing the bubble dispersion into the separation tank. An adjustable distributor plate is located at the slurry outlet. The distributor plate restricts the flow of slurry through the slurry outlet. The distributor plate is mounted to the rotating high shear element and rotates with the high shear element. In some embodiments, the distributor plate also controls the pressure within the sparger system.

Some embodiments of distributor cap could be bowl shaped or flat. Other embodiments of distributor cap could comprise a series of vanes that could be straight or curved and that extend radially outwards.

The high shear element could also comprise a plurality of rotating high shear elements located in series. The high shear element could also comprise both a rotating high shear element and a static high shear element. The rotating high shear element could comprise blades with openings to create additional shear within the sparger mechanism. The rotating high shear element could also comprise blades that are inclined to push slurry through the sparger mechanism. In certain instances, the sparger unit is surrounded by a center well.

In certain instances, the pressure across the sparging mechanism could be about 1 psig or less, during operation of the flotation separation system. The slurry being introduced into the sparger unit could be at a hydraulic pressure of about 25 psig or less. The slurry being introduced into the sparger unit could be at a hydraulic pressure of about 2 psig or less. The slurry being introduced into the sparger unit could be determined by the flow caused by gravity.

In certain instances, the first portion of the sparging mechanism is located above the second portion. In certain instances, first portion of the sparging mechanism is located below the second portion. The slurry could comprise an additive for modifying its specific chemistry.

When an additive is in the slurry, the additive could be selected from a group consisting essentially of a surface tension modifier, a collector, an extender, a depressant, and a pH modifier.

The flotation separation cell could comprise an overflow launder that is constructed to capture froth overflow from the separation tank. In certain instances, the flotation separation cell could comprise an underflow removal port that can be a drain, a pump, sand gates, or an overflow weir system. In certain instances, the flotation separation cell could comprise a froth washing system for washing the froth in the separation tank. In these instances, froth washing system can be a perforated wash pan, perforated pipes, height-adjustable perforated pipes, or a underwash system. Froth washing can also include water injection directly into the high bubble concentration zone or directly beneath said zone.

The gas inlet can receive gas from a gas compressor, a compressed gas tank, an educator, an aspirator, or a gas blower. In certain instances the flotation separation cell comprises a plurality of sparger units for introducing slurry at multiple locations within said separation tank. In these instances, the flotation separation cell could comprise a feed manifold distributor for distributing slurry to each sparger unit. In certain instances, the sparger unit comprises an adjustable distributor plate at the slurry outlet, which restricts the flow of slurry through the slurry outlet.

What is also claimed is a sparger unit for forming bubbles in a slurry in a flotation separation system. The slurry includes a hydrophobic species that can adhere to gas bubbles that form within the slurry. The sparger unit includes a slurry inlet, a slurry outlet, a sparging mechanism, a high shear element, and a gas inlet.

The slurry inlet is located at a first portion of a sparging mechanism and is for receiving a slurry. The gas inlet is also located at the first portion of the sparging mechanism and is for introducing a gas into the slurry. The gas itself has enough pressure to introduce the gas into the slurry.

The sparging mechanism is for dispersing the gas bubbles within the slurry. The effective open area within the sparging mechanism is substantially the same as the effective open area in the sparger unit that is both upstream and downstream from the sparging mechanism. The sparging mechanism is also constructed such that the slurry flows through the sparging mechanism in a substantially unrestricted manner. Furthermore, the pressure across the sparging mechanism is about 10 psig or less, during operation of the sparger unit.

A high shear element is located within the sparging mechanism, between the first portion and a second portion of the sparging mechanism. This high shear element is for shearing the gas into a bubble dispersion within the slurry for adhesion of the hydrophobic species to the bubble dispersion within the sparger unit. The high shear element comprises a rotating shaft and a rotating high shear element mounted to the rotating shaft. A slurry outlet is located at the second portion of the sparging mechanism. The slurry outlet is for discharging the slurry containing the bubble dispersion into the separation tank.

The sparger unit comprises an adjustable distributor plate at the slurry outlet. This adjustable distributor plate restricts the flow of slurry through the slurry outlet. The distributor cap is mounted to the rotating shaft and rotates with the high shear element. Some embodiments of distributor cap could be bowl shaped or flat. Other embodiments of distributor cap could comprise a series of vanes that could be straight or curved and that extend radially outwards.

The high shear element could be a rotating high shear element. The high shear element could also comprise a plurality of rotating high shear elements located in series. The high shear element could also comprise both a rotating high shear element and a static high shear element. The rotating high shear element could comprise blades with openings to create additional shear within the sparger mechanism. The rotating high shear element could also comprise blades that are inclined to push slurry through the sparger mechanism.

In certain instances, the pressure across the sparging mechanism could be about 1. psig or less, during operation of the sparger unit. The slurry being introduced into the sparger unit could be at a hydraulic pressure of about 25 psig or less. The slurry being introduced into the sparger unit could be at a hydraulic pressure of about 2 psig or less. The slurry being introduced into the sparger unit could be determined by the flow caused by gravity.

In certain instances, the first portion of the sparging mechanism is located above the second portion. In certain instances, first portion of the sparging mechanism is located below the second portion. The gas inlet can receive gas from a gas compressor, a compressed gas tank, an educator, an aspirator, or a gas blower. In certain instances, the sparger unit is surrounded by a center well.

Those skilled in the art will realize that this invention is capable of embodiments that are different from those shown and that details of the apparatus and methods can be changed in various manners without departing from the scope of this invention. Accordingly, the drawings and descriptions are to

be regarded as including such equivalent embodiments as do not depart from the spirit and scope of this invention.

BRIEF DESCRIPTION OF DRAWINGS

FIG. 17A shows an embodiment of a flotation separation cell that incorporates a center well;

FIG. 17B shows the center well shown in FIG. 17A showing the sparger unit within the center well;

FIG. 18A shows a different embodiment of a flotation separation cell in which the center well liquid level is maintained by adjusting the size of the orifices at the end of the center well based on pressure sensor readings;

FIG. 18B shows a different embodiment of a flotation separation cell in which the liquid level in the center well is maintained by adjusting the inflow of slurry to the flotation separation cell;

FIG. 18C shows a different embodiment of a flotation separation system comprising a number of flotation separation cells in series in which the liquid level in the center well for each flotation separation cell is maintained by adjusting the inflow of slurry to each flotation separation cell;

FIG. 19 is a perspective view of a flotation separation cell with four sparger units that feed slurry from the bottom of the separation tank;

FIG. 20 is a perspective view of a flotation separation cell with four sparger units that feed slurry through the sidewalls of the separation tank;

FIG. 21 is a perspective view of a flotation separation cell in which the underflow removal port leaves through the side of the separation tank;

FIG. 22 is a view of an embodiment of a sparger unit showing the rotating high shear element of the sparging mechanism and a rotating distributor plate;

FIG. 22A shows an embodiment of a flotation separation cell that incorporates the sparger unit of FIG. 22;

FIG. 23A is a perspective view of one-half of the distributor plate of FIG. 22;

FIG. 23B is a top view of a complete distributor plate of FIG. 22;

FIG. 24A is a bottom perspective view of one-half of another embodiment of rotating distributor plate with straight vanes on the underside of the distributor plate;

FIG. 24B is a bottom view of a complete distributor plate of FIG. 24A;

FIG. 25A is a bottom perspective view of one-half of another embodiment of rotating distributor plate with curved vanes on the underside of the distributor plate;

FIG. 25B is a bottom view of a complete distributor plate of FIG. 25A; and

FIG. 26 is an embodiment of a standalone sparger unit.

DETAILED DESCRIPTION

Referring to the drawings, some of the reference numerals are used to designate the same or corresponding parts through several of the embodiments and figures shown and described.

Corresponding parts are denoted in different embodiments with the addition of lowercase letters.

Variations of corresponding parts in form or function that are depicted in the figures are described. It will be understood that variations in the embodiments can generally be interchanged without deviating from the invention.

Flotation separation is commonly used in the minerals industry to separate mineral species in suspension in liquid slurries. Such mineral species are often suspended with a mixture of unwanted constituent species. Flotation separators currently in common use require an extensive applica-

tion of large amounts of energy for maintaining the slurry in suspension and creating a gas dispersion.

However, effective flotation separation is possible with the embodiments depicted herein without the need for high energy consumption. In one embodiment, shown in FIG. 1, a flotation separation system comprises at least one flotation separation cell 10 in a hydraulic system for the partitioning and recovery of the constituents of a slurry. The flotation separation cell 10 comprises at least one sparger unit 12 in which gas is introduced into the slurry. The sparger unit 12 includes a sparging mechanism 42 for sparging gas into a bubble dispersion within the slurry.

The sparging mechanism 42 is configured such that slurry flow through it is substantially unrestricted. The effective open area in the sparging mechanism 42 is substantially the same as the effective open area in the sparger unit 12 upstream and downstream of the sparging mechanism 42. This ensures a low pressure drop across the sparging mechanism 42 that allows for a lower pressure and flow rate of slurry through the sparger unit 12 and represents a significant energy savings for the flotation separation system. The pressure drop across the sparging mechanism 42 is about 10 psig or less. The operation of various embodiments of sparger units 12 is described in further detail below.

The sparger unit 12 feeds the slurry and bubble dispersion mixture to a separation tank 14. The separation tank 14 comprises an overflow launder 16, an underflow removal port 18, and a froth washing system 20. The overflow launder connects to an overflow drain 22. The flotation separation cell 10 may be supported by legs 24 or by any other means required by the particular application. The flotation separation cell 10 may even be placed directly on the floor if warranted by the design of the facility to which the flotation separation cell 10 is installed. The separation tank 14 requires no additional equipment within the tank to assist in froth formation (as discussed in more detail below) or to maintain the slurry in suspension. This represents a further energy savings in the overall operation as compared to conventional flotation separation systems, column flotation separation systems, and packed column flotation separation systems. The operation of the flotation separation system is presented in more detail below.

The flotation slurries typically include hydrophobic and hydrophilic species. Flotation separation takes advantage of the differing hydrophobicity of these species. When bubbles of gas are introduced into the slurry, the hydrophobic species within the slurry tend to selectively adhere to the bubbles while hydrophilic species tend to remain in suspension. Sparging, or breaking up, the bubbles into a bubble dispersion of many smaller bubbles increases the available bubble surface area for hydrophobic species adhesion. The bubbles, with the adhered hydrophobic species, tend to rise above the slurry and form a froth in the separation tank 14 that is easily separated from the remainder of the slurry for further processing to recover the adhered hydrophobic species. In the embodiment shown in FIG. 1 removal of the froth is accomplished by overflowing the froth from the separation tank 14 into the overflow launder 16 and draining the collected froth through the overflow drain 22 to downstream processes. The species not adhered to the froth remain in the slurry and are discharged through the underflow removal port 18 for further processing. Further processing can include a subsequent stage of froth formation to catch hydrophobic species that for whatever reason were not captured in the preceding step.

Flotation separation systems are typically part of larger hydraulic systems that process slurry over a number of steps.

The liquid portion of the slurry is typically water. The chemistry of the slurry is often adjusted with additives to assist in recovering a target component depending on the constituent species of the slurry. Surface tension modifying reagents, also known as frothers, are often added to slurries to assist in bubble formation. There are many types of frothers, including alcohols, glycols, and various blends.

Sometimes the target species for recovery from the slurry are naturally hydrophobic, for example coal. But in slurries in which the target species are not hydrophobic, chemicals additives, also known as collectors, are introduced to chemically activate them. Collectors include fuel oil, fatty acids, xanthates, various amines, etc.

Some target species are quasi-hydrophobic. For example, oxidized coal tends to be less hydrophobic and is more difficult to recover from a slurry than unoxidized coal. Chemical additives, called extenders, are used to increase their hydrophobicity. Examples of extenders are diesel fuels and other fuel oils.

Chemical additives called depressants are used to reduce the hydrophobicity of a species. For example, in the recovery of iron ore, various types of starches are used to depress the bubble adhesion response of iron ore so that only silica can be floated in the froth from the slurry. If the depressants are not added, a portion of the iron ore will also adhere to bubbles and float within the froth.

Because the pH of the slurry can affect froth formation, other chemical additives are introduced to modify the pH of the slurry. Acids or bases are added as needed to adjust the pH depending on the composition of the slurry.

In mineral flotation, the recovery of a particular species is predominantly controlled and proportional to two parameters: reaction rate and retention time. Recovery can be generally represented by the following equation:

$$R=k\alpha T$$

[1]

Where R is the recovery of a particular species, k is the reaction rate of adhesion of a species to a bubble, and T is the retention time of the slurry in the flotation separation system. An increase in either parameter provides a corresponding increase in recovery, R . The reaction rate, k , for a process is indicative of the speed at which the flotation separation will proceed and can be a function of several parameters including, but not limited to, gas introduction rate, bubble size, species size, and chemistry. The reaction rate, k , is increased when these parameters are adjusted to maximize the probability that a hydrophobic species will collide with and adhere to a bubble and to reduce the probability that a hydrophobic species will detach from a bubble. The probability of attachment is controlled by the surface chemistry of both the species and the bubbles in the process stream and is increased when the probability of a collision between a hydrophobic species and a bubble increases. The probability of collision is directly proportional to the concentration of hydrophobic species within the sparging region. The probability of detachment is controlled by the hydrodynamics of the flotation separation cell. As such, aeration of the slurry prior to its introduction to a separation tank is the preferred method of sparging as this ensures that the maximum amount of floatable species is concentrated within the sparging unit to obtain a high recovery of the hydrophobic species. The embodiments described herein aim to increase the reaction rate, k , which means that a lower retention time, T , and thereby a smaller separation tank, can be used to obtain a suitable recovery, R .

In the embodiments disclosed herein, the reaction rate, k , of Equation [1] is increased by forcing the bubble-particle

contact with high particle and air bubble concentrations and imparting significant energy within the bubble/particle contacting zone. Recovery, R , can also be represented in turbulent systems described herein as a function of the bubble concentration, C_b , particle concentration, C_p , and specific energy input, E , as follows:

$$R \propto C_b C_p E$$

[2]

The embodiments disclosed herein efficiently pre-aerate slurry in the sparger units 12 of the flotation separation cell 10 prior to injection of the slurry and gas mixture into the separation tank 14. Slurry introduced into the sparger unit 12 passes through a sparging mechanism 42, described in more detail below. The sparging mechanism 42 sparges the gas in the slurry into a bubble dispersion creating a relatively large surface area for hydrophobic species attachment within the sparger unit 12 such that hydrophobic species adhesion to bubbles occurs substantially in the sparger unit 12 before the slurry and the bubble dispersion is discharged into the separation tank 14. This approach ensures that bubbles are generated in the presence of the slurry prior to any dilution with wash water (if used), thus maintaining the maximum particle concentration (C_p). Additionally, the sparger assembly 30 is operated at a very high air fraction (up to >50%), insuring that the bubble concentration (C_b) is maximized. Finally, the design of the sparging mechanism 42 in the sparger unit 12 is such that maximum energy is imparted to the slurry for the sole purpose of bubble-particle contacting. As a result, the contact time is reduced by several orders of magnitude over prior art column and conventional flotation separators. After contacting, the slurry is discharged to the separation tank 14 for phase separation (slurry and froth) and froth washing (if used). Since phase separation is a relatively quick process, the overall separation tank 14 size is significantly reduced.

The sparging mechanism 42 is configured such that slurry flow through it is substantially unrestricted. The effective open area in the sparging mechanism 42 is substantially the same as the effective open area in the sparger unit 12 upstream and downstream of the sparging mechanism 42. This ensures a low pressure drop across the sparging mechanism 42 that allows for a lower pressure and flow rate of slurry through the sparger unit 12 and represents a significant energy savings for the flotation separation system. The pressure drop across the sparging mechanism 42 is about 10 psig or less. Nevertheless, the embodiments depicted herein are able to operate with pressure drops of about 1 psig or less.

As the bulk of the hydrophobic species adhesion to a bubble occurs in the sparging unit 12, the flotation separation cell 10 does not require the slurry to be introduced at a high velocity and/or a high pressure. The slurry may be pumped under pressure into the sparger unit 12 if the hydraulics of the flotation separation system require, but this need only be sufficient to provide enough hydraulic pressure for the slurry to flow through the flotation separation system. Slurry can be introduced into the flotation separation cell 10 at the slurry inlet of the sparger unit 12 at a hydraulic pressure of about 25 psig or less. The embodiments depicted herein are able to operate at slurry introduction hydraulic pressures of 2 psig or less.

The relatively low hydraulic pressure gradient that the slurry must overcome represents an energy savings during the operation of the flotation separation cell 10. The hydraulics of a flotation separation cell 10 can be adjusted in various embodiments by, for example, adjusting the height of the sparger units 12 in relation to the height of the slurry

in the separation tank 14 or by adjusting the entry point of shiny to the flotation separation cell 10.

Similarly, the sparging mechanisms 42, described in more detail below, do not require gas to be introduced at a high pressure. The gas introduction pressure need only be high enough to form bubbles in the slurry and the sparging mechanisms 42 described herein will sparge the bubbles into effective bubble dispersions. The low pressure and flow requirements for both slurry and gas introduction represent significant energy savings when compared to conventional flotation separation systems, column flotation separation systems, and packed column flotation separation systems.

As has been already discussed, with an increase in the rate of reaction provided by the method of pre-aeration, there is a corresponding decrease in the required retention time for a given application. Therefore, the same flotation recovery can be obtained in a smaller volume than with prior art systems. As the bubble and species attachment substantially occurs in close proximity to the sparging mechanism 42 in the sparger units 12, described in more detail below, and not within the separation tank 14 itself, the separation tank 14 is only required to provide time for the slurry and bubble phases to separate. A smaller separation tank 14 can be utilized without additional equipment in the separation tank when compared to conventional flotation separation systems, column flotation separation systems, and packed column flotation separation systems. The smaller and simpler flotation separation cell 10 allows for greater flexibility in designing flotation separation systems for particular applications. Energy is also not consumed to maintain the slurry in suspension in the separation tank 14.

Because the separation tank 14 is used solely for froth separation, and does not require any additional equipment to maintain the slurry in suspension, the embodiments described herein are able to maintain a relatively deep froth in the separation tank 14 with no additional turbulence imparted to the separation tank 14. Therefore, unlike with conventional flotation separation systems, the addition of wash water from the froth washing system 20 (described in more detail below) to clean the froth, does not affect the retention time of the froth, in the separation tank 14. It is therefore possible to have effective froth washing in the flotation separation systems described herein.

As the energy input to the system is focused specifically on creating fine bubbles and not in maintaining the particles in suspension, the overall energy input is reduced. While a compressor may be used to introduce gas into the flotation separation system, because the sparging mechanism 42 operates at atmospheric pressure a compressor is not required to overcome the hydrostatic system head. Instead, a simple blower can be used, providing energy and maintenance savings. The energy reduction, of course, implies reduced operating costs. Finally, the smaller separation tank 14 requirements reduce equipment and installation costs. Structural steel requirements are significantly less due to the reduction in tank weight and live load. The space requirement is less than that required for equivalent conventional column flotation separation. Shipping and installation is also simplified since the units can be shipped fully assembled and installed without field welding.

Depending on the operational requirements of the system to which the flotation separation system is installed, FIG. 2 shows how the flotation separation cell 10a can be designed with multiple sparger units 12a, in this case three, with an appropriately sized separation tank 14a. A feed manifold distributor 26a having distributor pipes 28a may be used to evenly distribute slurry to each sparger unit 12a.

In one embodiment of the sparger unit best understood by comparing FIGS. 3 and 4, each sparger unit 12b comprises a sparger assembly 30b that allows for the passage of feed slurry to a separation tank (14 and 14a in FIGS. 1 and 2). 5 The size of the sparger assembly 30b is dictated by the size of the flotation separation system in which the sparger unit 12b is installed and is primarily intended to direct the slurry discharge to an appropriate location within the separation tank 14. The slurry should be discharged low enough in the separation tank 14 so as to not interfere with froth formation at the top of the separation tank 14.

Slurry is introduced into the sparger unit 12b through the slurry inlet 38b and passes through a sparging mechanism 42b. As has been already discussed, the sparging mechanism 42b is configured such that slurry flow through it is substantially unrestricted. The effective open area in the sparging mechanism 42b is substantially the same as the effective open area in the sparger unit 12b upstream and downstream 15 of the sparging mechanism 42b. The pressure drop across the sparging mechanism 42b is about 10 psig or less.

In the embodiments depicted in FIGS. 3 and 4, the sparging mechanism 42b comprises a rotating high shear element 32b attached to a rotating shaft 34b that is powered 20 by an electric motor 36b. The slurry may be gravity fed if there is enough hydraulic pressure to ensure that the slurry will flow through the flotation separation system. If the hydraulics of the system requires the slurry to be pumped, the slurry need only be pumped with sufficient pressure to 25 ensure passage of the slurry through the flotation separation system. Nevertheless, the sparger unit 12b will function well over a broad range of slurry flow rates and pressures. Slurry can be introduced into the slurry inlet 38b of the sparger unit 12b at a hydraulic pressure of about 25 psig or less. The 30 sparger unit 12b can operate at a slurry hydraulic pressure of about 2 psig or less.

Gas (typically air) is introduced to the sparger unit 12b through gas inlets 40b that are supplied from a gas injection system (discussed in more detail below). The passing slurry 40 flow immediately shears the gas to form bubbles as the gas enters the sparger unit 12b through the gas inlets 40b. The gas need not be at a high pressure for effective bubble formation in the slurry. Even at high slurry feed rates, the gas 45 flow and pressure needs only be high enough to allow bubble formation in the slurry.

The bubbles are sheared into smaller bubbles as the slurry passes through the sparging mechanism 42b and forms a fine bubble dispersion within the slurry. The formation of the bubble dispersion within the sparger unit 12b exposes a 50 larger volume of slurry to the surface of the bubbles. This increases the incidences of hydrophobic species collision with the bubbles and increases the probability of adhesion of a hydrophobic species to a bubble. In the embodiment depicted in FIGS. 3 and 4, this gas shearing is aided with the 55 rotating high shear element 32b. The rotating high shear element 32b is intended to shear gas bubbles only and is not intended to agitate or mix the entire slurry volume, therefore, the electric motor 36b need only be large enough to drive the rotating high shear element 32b. This represents a 60 significant energy savings over flotation separation systems that require agitation of the slurry for bubble shearing.

The creation of the bubble dispersion with the sparger unit 12b exposes the entire volume of slurry to the surface of a bubble. Therefore the bulk of the adhesion of a hydrophobic species to a bubble is likely to occur within the sparger assembly 30b, in and downstream of the sparging mechanism 42b.

11

Once the slurry has passed through sparging mechanism 42b, the slurry and the bubble dispersion is discharged into a separation tank (14 and 14a in FIGS. 1 and 2) through a slurry outlet 51b. The velocity of slurry discharge is adjusted by changing the location of the distributor plate 44b using adjustment bolts 46b.

As shown in the embodiment depicted in FIG. 5, the sparger assembly 30c can contain opposing static vanes 48c to increase the shearing of gas bubbles in the sparging mechanism 42c. It will be appreciated that the rotating high shear elements 32b and 32c, as shown in FIGS. 4 and 5, and the static vanes 48c shown only in FIG. 5 are for example purposes only and that other configurations of rotating high shear elements and static vanes are possible and intended to be covered herein.

In the embodiments shown in FIGS. 4 and 5, the gas inlets 40b and 40c are situated upstream of the sparging mechanisms 42b and 42c. However, the embodiment of sparging mechanism 42d depicted in FIGS. 6A and 6B has gas inlets 40d over the length of the sparging mechanism 42d. The gas inlets 40d are supplied by gas from an outer sleeve 45d that connects to the gas injection system (discussed in more detail below) through a hose connection 47d. The gas inlets 40d are shown in more detail in FIGS. 6C through 6E and comprise an elastomeric check valve 49d that prevents the backflow of slurry into the outer sleeve 45d.

The rotating high shear elements 32b and 32c and the static vanes 48c in the sparging mechanisms 42b and 42c serve to break up the bubbles formed at the gas inlets 40b and 40c into smaller bubbles to increase the cumulative surface area. Variations of air sparging units are possible in which the gas is introduced to the slurry through the sparging mechanisms such that the bubbles formed are of an appropriate size to form a bubble dispersion.

As can best be understood by comparing the alternate arrangement in FIGS. 7A through 7E, the top of the sparger unit 12e comprises a gas supply coupling 50e to the gas injection system (discussed in more detail below). Gas is supplied through a gas supply tube 52e to the sparging mechanism 42e. The bottom of the supply tube 52e ends in a series of slots 56e that define the length of the sparging mechanism 42e. In this embodiment, the sparging mechanism 42e comprises a series of discs 58e that are stacked up to at least the length of the slots 56e in the gas supply tube 52e. Each disc 58e has a series of grooves 60e that run from the slots 56e in the gas supply tube 52e to the outer edge of the disc 58e. When the discs 58e are stacked on top of each other, the grooves 60e define channels for the gas to mix with the passing slurry. In this embodiment each groove 60e acts as a gas inlet for the sparger unit 12e. The number and size of the grooves 60e and the thickness and the number of the discs 58e are determined by the particular application. The smaller the grooves 60e, the smaller the bubbles formed when the passing flow of slurry sparges the gas. The smaller gas bubbles created by the sparging mechanism 42e in this embodiment are of an appropriate size to form a bubble dispersion. Therefore the grooves 60e also serve as the high shear element of this embodiment of sparger unit 12e. This sparger unit 12e requires even less energy to operate than the embodiments presented earlier.

Nevertheless, the sparging mechanism 42e is configured such that slurry flow through it is substantially unrestricted. The effective open area in the sparging mechanism 42e is substantially the same as the effective open area in the sparger unit 12e upstream and downstream of the sparging mechanism 42e. The pressure drop across the sparging mechanism 42e is about 10 psig or less.

12

The sparger units 12e can be easily disconnected from the gas injection system (discussed in more detail below) and water, gas, or another cleaning agent can be forced through the grooves 60e to facilitate cleaning of the sparging mechanism 42e. The discs 58e may be made from metal, plastic, polyurethane, ceramics, or any other material that would be appropriate for the particular application. While the discs 58e depicted in FIGS. 7A through 7E have grooves 60e on only one side, FIG. 8 shows a disc 58f having grooves 60f on both sides.

The sparger units 12g shown in FIGS. 9A through 9C are a variation of the sparger unit 12e of FIG. 7A. This embodiment incorporates a cleaning mechanism for the sparging mechanisms 42g. As can be best understood by comparing FIGS. 9A through 9C, the sparger unit 12g includes an inner gas supply tube 52g connected by a gas supply coupling 50g to the gas injection system (discussed in more detail below). A cleaning fluid coupling 53g allows for the introduction of a cleaning fluid into the sparger unit 12g. The fluid could be water, compressed gas, or other fluid that could be fed at high pressure to clear debris or clean out the grooves on the discs 58g during routine maintenance or as needed.

The embodiment of sparger unit 12h shown in FIG. 10 shows the sparging mechanism 42h comprising a high frequency displacement device 54h. In this embodiment gas is introduced to the sparger unit 12h similar to the embodiment shown earlier, but other gas injection mechanisms are possible. The high frequency displacement device 54h generates a high frequency vibration at the high shear element 32h that sparges bubbles formed by the gas inlets (not shown) as the bubbles pass the sparging mechanism 42h. This vibration shears the bubbles to create the fine bubble dispersion in the slurry. Nevertheless, the sparging mechanism 42h is configured such that slurry flow through it is substantially unrestricted. The effective open area in the sparging mechanism 42h is substantially the same as the effective open area in the sparger unit 12h upstream and downstream of the sparging mechanism 42h. The pressure drop across the sparging mechanism 42h is about 10 psig or less.

As shown in FIG. 11, other embodiments of sparger units 12i are possible in which the sparging mechanism 42i extends across the length of the sparger assembly 30i. These embodiments function similarly to the sparger unit 12b shown and described in FIG. 4 above, however any of the other embodiments described above would work equally well. The sparging mechanism 42i shown in FIG. 11 comprises a series of rotating high shear elements 32i that serve to further break up and shear introduced gas into fine bubbles. In this embodiment, the blades of the high shear elements 32i have openings cut into them to further shear the bubbles. The stacked rotating high shear elements 32i increase the amount of sparging each unit volume of slurry 55 is exposed to as it moves through the sparger unit 12i. As with the embodiments discussed above, the energy input into the sparger unit 12i is for shearing introduced gas into a fine bubble dispersion and not for agitating the slurry. The sparger unit 12i could also incorporate opposing static vanes 60 as shown for example in FIG. 5 to increase the shearing of gas bubbles in the sparging mechanism. The embodiment shown in FIG. 11 shows the outlets 51i from the sparger unit 12i as holes cut into the side of the sparger assembly 30i. The number, shape, and arrangement of rotating high shear elements 32i and/or static vanes can vary. It will be appreciated that the rotating high shear elements 32i, and the static vanes shown only in FIG. 5 are for example purposes only

and that other configurations of rotating high shear elements and static vanes are possible and intended to be covered herein.

Regardless of the embodiment of sparger unit **12j** used, the operation of the flotation separation system is demonstrated in the flotation separation cell **10j** depicted in FIG. 12. The flotation separation cell **10j** shows three sparger units **12j**, but the operation described is applicable to any number of sparger units **12j**. A flotation separation cell having only one sparger unit (for example as shown in FIG. 1) would not require a feed manifold distributor as shown in FIG. 12.

Slurry is fed to the feed manifold distributor **26j** from upstream operations in which the flotation separation cell **10j** is installed. As has already been discussed, the slurry may be pumped under pressure into the sparger unit if the system hydraulics require, but this need only be sufficient to provide enough hydraulic pressure for the slurry to flow through the flotation separation cell **10j**. Slurry can be introduced into the flotation separation cell **10j** at the slurry inlet **38j** of the sparger unit **12j** at a hydraulic pressure of about 25 psig or less. The feed manifold distributor **26j** evenly distributes slurry to the slurry inlets **38j** of the sparger units **12j** through distributor pipes **28j**. The pressure drop across the sparging mechanisms of the sparger units **12j** is about 10 psig or less.

Gas, typically air, is supplied to the sparger units **12j** from the gas injection system **62j**. As discussed earlier, gas introduction pressure need only be high enough to allow bubbles to form in the slurry. The gas injection system **62j** consists of a pressure regulator **64j**, a gas flow meter **66j**, a flow regulating valve **70j**, and a gas manifold distributor **72j**. The gas manifold distributor **72j** connects the gas injection system to the sparger units **12j**. A low-pressure gas blower (not shown) would preferably supply gas to the gas injection system **62j**. Alternatively, compressed gas tanks, an educator, an aspirator, or gas compressors (not shown) can be employed.

The operation of sparger units **12j** is as previously described. The slurry and the bubble dispersion are discharged into the separation tank **14j**, which allows for the separation of the floatable and non-floatable hydrophobic species. A froth of bubbles with adhered floatable hydrophobic species forms above the slurry at the top the separation tank **14j**. The froth can be removed from the top of the separation tank for further processing. In one embodiment, the froth overflows the separation tank into a product launder **16j**. The froth overflow is discharged from the product launder **16j** through the overflow drain **22j** for further processing.

Non-floatable hydrophobic species, heavier particles that do not adhere to the froth, and any hydrophobic species that for whatever reason do not adhere to the froth fall to the bottom of the separation tank **14j** and are drained through the underflow removal port **18j** for further processing. The rate of underflow discharge is controlled through a control valve **74j** that is actuated based on a signal provided by a process controller **76j**. The output of the process controller **76j** is proportional to an input signal derived from a pressure sensor **78j** located on the side of the separation tank **14j**. Alternatively, various other level control systems can be employed such as pumps, sand gates, and overflow weir systems.

The froth at the top of the separation tank is washed with the froth washing system **20j**. Water or any other cleaning liquid used for froth washing is controlled by the froth washing control system **80j**. In the froth washing system **20j**,

clean water is evenly distributed across the top of the froth using a perforated wash pan. Alternatively, the froth washing system **20j** can comprise rings of perforated pipes, height-adjustable perforated pipes, or an underwash system (not shown). The flow of wash water is controlled using a flow meter **82j** and a flow control valve **84j**.

A pilot scale flotation separation system similar to the flotation separation cell depicted in FIG. 1 is currently in operation. The pilot flotation separation cell comprises a separation tank that is 48 inches in diameter and about 60 inches deep and has a single sparger unit that is about 4 inches in diameter. The sparger unit processes coal slurry at the rate of about 600 gpm. The sparging mechanism is similar to the embodiment depicted in FIG. 4. The high shear element of the sparger unit rotates at about 1,200 rpm. Gas is introduced at the gas inlets at about 60 scfm. Slurry enters the sparging mechanism by gravity and has been measured at the sparging mechanism to have a hydraulic pressure of less than 1 psig. During normal operating conditions, slurry fills the separation tank up to 3 feet from the bottom with froth filling an additional 2 feet above the slurry. The froth is washed with clean water using clean water sprayed over the top of the froth through an arrangement of perforated pipes at a rate of up to 60 gpm.

The flotation response of several coal types were investigated including the Amburgy, Hazard No. 4, Red Ash, Gilbert and Pocahontas No. 3 seams. For the Amburgy and Hazard No. 4 seams (FIG. 5), the ash content of the flotation feed averaged 52%, by weight. Combustible recovery ranged from 30% to 78% depending on operating parameters. The average combustible recovery for a single-stage of treatment was approximately 60% with a product ash content of 6%. Similarly, an average combustible recovery of between 40% and 50% was achievable while treating Red Ash, Gilbert, or Pocahontas No. 3 coal seams. For these coals, the product ash averaged less than 4% by weight. The lower feed ash (i.e., 18%) for these seams resulted in a slightly lower range of combustible recovery. This finding is not unexpected given that as the feed ash decreases, the amount of floatable coal increases for a given volume flow and retention time.

While hydrophobic species adhesion to the bubble dispersion in the sparger units **12j** allows for a high recovery of hydrophobic species in the slurry, not all of the hydrophobic species in the slurry will adhere to a bubble. Furthermore, there is a reduction in bubble surface area at the interface of the froth and the slurry in the separation tank **14j** that leads some adhered hydrophobic species to fall off and be lost to the underflow nozzle **18j**. As has been already discussed, the flotation separation system described herein requires a smaller separation tank size than conventional flotation separation systems. As shown in FIGS. 13 and 14, this allows for several flotation separation cells **10j** to be easily combined in-series to negate the effects of mixing and hydrophobic species bypass of the bubble dispersion.

The fundamental principle favoring a tank-in-series approach is simple and well known: for an equivalent retention time, a series of perfectly mixed tanks will provide a higher recovery than a single cell. This point is illustrated by the following equation:

$$R = 1 - \left(\frac{N}{N + k\tau} \right)$$

where the change in recovery, R , is a function of the number of perfect mixers (N) for a system with a constant process rate (k) and retention time (τ). As shown in FIG. 15, increasing the number of mixers in series, at a constant value of $k\tau$, results in an increase in recovery. For example, for a $k\tau$ value of 4, changing from one perfectly mixed tank to four cells in series results in an increased recovery of nearly 15%.

This concept can be understood by examining the basic operation of a conventional flotation cell. Each cell contains a mixing element that is used to disperse air and maintain the solids in suspension. As a result, each cell behaves "almost" as a single perfectly mixed tank. By definition, a perfectly mixed tank has an equal concentration of material at any location in the system. Therefore, a portion of the feed material has an opportunity to immediately short circuit to the tailings discharge point. In a system using a single large cell, this would imply a loss in recovery. However, by discharging to a second tank, another opportunity exists to collect the floatable material. Likewise, this is also true with the third and fourth cell in the series. Of course, at some point, the law of diminishing returns applies. In conventional flotation systems, this is typically after four or five cells in series. However, the recovery gain with each cell requires additional energy.

Based on the same principle, the in-series arrangements shown for example in FIGS. 13 and 14 reduce the inadvertent bypass of feed slurry from individual flotation separation cells $10j$. In such modular in-series arrangements, the slurry that leaves through the underflow nozzle $18j$ of one separation tank $14j$ is redirected to the sparger units $12j$ of the next flotation separation cell $10j$. This arrangement increases the particulate recovery from a slurry stream. The flotation separation cells $10j$ can be placed in a modular vertical arrangement (as in FIG. 13), a staggered horizontal arrangement (as in FIG. 14), or any arrangement that allows for a sufficient hydraulic pressure to convey the slurry from cell to cell. If such a configuration is not possible in the particular application, the slurry could be pumped to each subsequent cell in the series. The number of required flotation separation cells $10j$ will be dependent on the specific application.

In any of the embodiments herein, it is also possible to divert a portion of the slurry discharge from the underflow removal port 18 or the overflow drain 22 back to the initial sparger unit 12 (or the feed manifold distributor $26a$ in flotation separation systems with more than one sparger unit $12a$). This would serve to recycle any chemical additives used to promote frothing and would reduce the materials cost of operation. Similarly, in the embodiments shown in FIGS. 13 and 14, a portion of the discharge from the underflow removal port $18j$ or the overflow drain (not shown) from the last flotation separation cell $10j$ can be diverted back to the feed manifold distributor $26j$ of the first flotation separation cell $10j$.

The energy requirements of the flotation separation systems described herein are orders of magnitude lower than conventional flotation separation systems, column flotation separation systems, and packed column flotation separation systems for processing a similar amount of slurry with comparable recovery results. A conventional flotation separation system that processes 3,000 gpm of coal slurry may typically comprise 6-8 separation tanks in series, with each separation tank containing a 20-30 HP motor to turn impellers to mix the slurry in the tanks, for a total of about 200 HP for mechanical agitation. Such a conventional system would require an additional 150 HP to power the air blower system

for sparging gas. A typical column flotation separation system that processes 3,000 gpm of coal slurry requires slurry recirculation pumps that could require around 200 HP to operate. An additional 200 HP would be required to operate the air compressors for sparging bubbles. A packed column flotation separation systems of similar 3,000 gpm capacity typically would have similar requirements to a typical column flotation system with about 200 HP for recirculation pumps and about 200 HP for air compressors.

10 In contrast, a flotation separation system as described herein for processing 3,000 gpm of coal slurry, comprising three flotation separation cells in series, each cell having a single sparger unit with sparging mechanisms that comprise a series of rotating high shear elements (similar to those shown in FIG. 11) would require significantly less energy. The energy required to power each sparger unit in such a system would be around 20 HP for a total of 60 HP for all three sparger units. The energy required by the gas supply system would be about 70 HP for all three sparger units. 15 Each separation tank in such a configuration would be about 11 feet in diameter and about 6 feet deep. This represents a significant savings in energy consumption and material requirements.

The small footprint required for the flotation separation cell $10j$ suggests that it can be used to relieve the loading on existing conventional flotation cells $85j$ as shown for example in FIG. 16A. In such an arrangement, slurry that has been processed in the flotation separation cell $10j$ and discharged through the underflow removal port $18j$ is fed to the inlet $86j$ of a conventional flotation cell $85j$. Collected froth from the flotation separation cell's $10j$ overflow launder $16j$ and overflow drain $22j$ is combined with product collected from the conventional flotation cell's $85j$ discharge $87j$. As a significant portion of the hydrophobic species in the slurry has been removed by the flotation separation cell $10j$, the reduced loading to the conventional flotation cell $85j$ leads to an overall increase in its performance and an improved overall recovery percentage of the hydrophobic species from flotation separation.

20 Similarly, as shown in FIG. 16B, a flotation separation cell $10j$ can be located upstream of an existing column flotation cell $88j$. In such an arrangement, slurry that has been processed in the flotation separation cell $10j$ and discharged through the underflow removal port $18j$ is fed to the inlet $89j$ of a conventional column flotation cell $88j$. Collected froth from the flotation separation cell's $10j$ overflow launder $16j$ and overflow drain $22j$ is combined with product collected from the column flotation cell's $88j$ discharge $91j$. As a significant portion of the hydrophobic species in the slurry has been removed by the flotation separation cell $10j$, the reduced loading to the column flotation cell $88j$ leads to an overall increase in its performance and an improved overall recovery percentage of the hydrophobic species from flotation separation.

25 The pilot scale test indicated that there would be additional benefit to the flotation separation systems disclosed herein if a center well $90k$ were to be incorporated in the separation tank $14k$, as shown in FIG. 17A. As can be best understood by comparing FIGS. 17A and 17B, the center well $90k$ fits around the outside of the sparger unit $12k$ and comprises a tube that runs the height of the separation tank $14k$. Outlets $92k$ near the bottom of the center well $90k$ allow for the slurry discharged from the sparger unit $12k$ to enter the separation tank $14k$.

30 The purpose of the center well $90k$ is to ensure that the sparger assembly within the center well $90k$ remains submerged below the liquid level and to aid in efficient bubble

formation and promote efficient bubble/particle interaction. At low flows, the center well 90*k* liquid level will be at the same level as that of the surrounding separation tank 14*k*. However, at higher flows, the level within the center well 90*k* will be higher than that of the surrounding separation tank 14*k*. The higher level ensures that there is no chance for air to coalesce within the sparger unit 12*k* and ultimately reduces burping and inefficient contacting within the sparger unit 12*k*. The liquid level in the center well 90*k* can be determined by reading a low-pressure pressure gauge (not shown) that is installed on the slurry inlet 38*k*. In order to ensure that the center well 90*k* stays full, the center well 90*k* must be engineered such that it flushes just slightly slower than it fills. Only a positive pressure is required to indicate that the center well 90*k* is full.

Level control in the center well can be maintained in several ways as shown in FIGS. 18A through 18C. As shown in FIG. 18A, the center well 90*l* is constructed such that the size of the outlets 92*l* can be continuously adjusted. A low-pressure gauge 94*l* installed at the slurry inlet 38*l* monitors the pressure in sparger unit 12*l*. A PID control loop 96*l* adjusts the outlet 92*l* size in response to changes in the pressure readings—an increase in pressure above a preset limit will trigger the PID control loop 96*l* to increase the outlet 92*l* size to allow more slurry to leave the sparger unit 12*l* and the center well 90*l*; a decrease in pressure below a preset limit will trigger the PID control loop 96*l* to decrease the outlet 92*l* size which will retain more slurry in the center well 90*l* and keep the sparger unit 12*l* submerged. It was contemplated that direct level control of the level of the separation tank 14*l* could be performed by using a PID process controller to throttle the outflow from the underflow nozzle 18*l* based on pressure readings in the separation tank 14*l*. While this method will ensure a consistent level in the separation tank 14*l*, it would not ensure that there is sufficient pressure within the center well 90*l*.

A simpler control scheme is shown in FIG. 18B that negates the need for a control mechanism to be placed within the separation tank 14*m*. In essence, the center well 90*m* level is maintained by controlling the flow from the inflow to the flotation separation system by automating a make-up valve 98*m* through a PID control loop 96*m* such that a low pressure reading from the low-pressure pressure gauge 94*m* triggers additional liquid, and hence flow, to be routed to the separation cell 10*m*.

This method can be easily applied to a series of separation tanks 10*n*, as shown in FIG. 18C. For the next cell in series for flotation separation systems that comprise a series of flotation separation cells 10*n*, a second PID control loop 100*n* controls the underflow nozzle 18*n* of the previous separation cell 10*n* in the series. These embodiments require only automation of the underflow nozzle 18*n* as per accepted industrial practice.

Other designs of flotation separation cells are also possible. FIG. 19 shows a flotation separation cell 10*o* in which the slurry enters the sparger units 12*o* from underneath the separation tank 14*o*. A feed manifold distributor 26*o* distributes slurry to each sparger unit 12*o* through distributor pipes 28*o* to the sparging mechanisms 42*o*. Gas is supplied to the sparger units as described above. The electric motors 36*o* that power the rotating high shear element (not shown) via rotating shafts 34*o* are located above the separation tank 14*o*. The electric motors 36*o* are supported in place with a support ring 90*o*. Slurry passes up through the sparging mechanism 42*o* and into the separation tank 14*o*.

FIG. 20 shows an embodiment of a flotation separation cell 10*p* in which the sparger units 12*p* are located on the side

of the separation tank 14*p*. In this embodiment the feed manifold distributor 26*p* is shown feeding the sparger units 12*p* from underneath the separation tank 14*p*. The feed manifold distributor 26*p* can also be located above the separation tank 14*p* as shown in earlier embodiments.

The underflow removal port 18*q* does not need to be located at the bottom of the flotation separation cell 10*q*. The embodiment shown in FIG. 21 shows how the underflow removal port 18*q* can remove slurry from the side of the separation tank 14*q*. The underflow removal port 18*q* has a right angle bend directed towards the bottom of the separation tank 14*q* to allow for a uniform withdrawal of slurry from the bottom of the separation tank 14*q*. The slurry can be withdrawn from the underflow removal port 18*q* by gravity as a drain or with a pump, sand gates, an overflow weir system, or any other appropriate mechanism.

FIGS. 22 and 22A show an embodiment of a flotation separation cell 10*r* in which the sparger unit 12*r* is located within a separation tank 14*r*. In this embodiment, the sparger unit 12*r* includes a sparging mechanism 42*r* for sparging gas into a bubble dispersion within the slurry. A slurry inlet 38*r* feeds slurry up into the sparger unit 12*r*. The sparging mechanism 42*r* is configured such that slurry flow through it is substantially unrestricted. The effective open area in the sparging mechanism 42*r* is substantially the same as the effective open area in the sparger unit 12*r* upstream and downstream of the sparging mechanism 42*r*. This ensures a low pressure drop across the sparging mechanism 42*r* that allows for a lower pressure and flow rate of slurry through the sparger unit 12*r* and represents a significant energy savings for the flotation separation system. The pressure drop across the sparging mechanism 42*r* is about 10 psig or less.

The sparging mechanism 42*r* comprises a rotating high shear element 32*r* attached to a rotating shaft 34*r* that is powered by an electric motor 36*r*. The slurry may be gravity fed if there is enough hydraulic pressure to ensure that the slurry will flow through the flotation separation system. If the hydraulics of the system requires the slurry to be pumped, the slurry need only be pumped with sufficient pressure to ensure passage of the slurry through the flotation separation system. Nevertheless, the sparger unit 12*r* will function well over a broad range of slurry flow rates and pressures. Slurry can be introduced into the slurry inlet 38*r* of the sparger unit 12*r* at a hydraulic pressure of about 25 psig or less. The sparger unit 12*r* can operate at a slurry hydraulic pressure of about 2 psig or less. In this embodiment, the slurry inlet 38*r* is located at the bottom of the sparger unit 12*r* so that slurry flows upwards through the device as indicated by the arrows in the figure. The sparger unit 12*r* has a flange with bolt holes 68*r* that allows the unit to be bottom fed as shown, for example, with the embodiments depicted in FIG. 19, however it would be understood that other configurations are also possible.

Gas (typically air) is introduced to the sparger unit 12*r* through gas inlets 40*r* that are supplied from a gas injection system (discussed in more detail below). In this embodiment, the air is injected down the rotating shaft 34*r*. Air enters through a sealed bearing housing (not shown) at the top of the rotating shaft 34*r* and travels through the rotating shaft 34*r* and exits from the gas inlets 40*r* into the sparger unit 12*r*. The passing slurry flow immediately shears the gas to form bubbles as the gas enters the sparger unit 12*r* through the gas inlets 40*r*. The gas need not be at a high pressure for effective bubble formation in the slurry. Even at high slurry feed rates, the gas flow and pressure needs only be high enough to allow bubble formation in the slurry.

The bubbles are sheared into smaller bubbles as the slurry passes through the sparging mechanism 42r and forms a fine bubble dispersion within the slurry. The formation of the bubble dispersion within the sparger unit 12r exposes a larger volume of slurry to the surface of the bubbles. This increases the incidences of hydrophobic species collision with the bubbles and increases the probability of adhesion of a hydrophobic species to a bubble. In the embodiment depicted in FIG. 22, this gas shearing is aided with the rotating high shear element 32r. The rotating high shear element 32r is intended to shear gas bubbles only and is not intended to agitate or mix the entire slurry volume, therefore, the electric motor 36r need only be large enough to drive the rotating high shear element 32r. This represents a significant energy savings over flotation separation systems that require agitation of the slurry for bubble shearing.

In addition, the rotating high shear elements 32r could have openings as depicted in FIG. 22. These openings create additional shear which assists in bubble formation. The blades of the rotating high shear elements 32r could also be partially inclined to help push the slurry through the system. The rotating high shear elements 32r induce low-pressure zones behind the rotating blades to induce cavitation. The blades can be configured and operated in such a way that the environment within the sparger unit 12r supports and induces cavitation within the slurry.

The creation of the bubble dispersion with the sparger unit 12r exposes the entire volume of slurry to the surface of a bubble. Therefore, the bulk of the adhesion of a hydrophobic species to a bubble is likely to occur within the sparger assembly 30r, in and downstream of the sparging mechanism 42r. Once the slurry has passed through sparging mechanism 42r, the slurry and the bubble dispersion is discharged into a separation tank (14 and 14a in FIGS. 1 and 2) through a slurry outlet 51r as shown by the arrows in the figure. The velocity of slurry discharge is adjusted by changing the location of the distributor plate 44r. In some variations of the sparger unit 12r could also incorporate static vanes as shown for example in FIG. 5 to increase the shearing of gas bubbles in the sparging mechanism. The combination of fixed vanes against the rotating vanes creates additional shear for bubble dispersion. The interaction of the rotating high shear elements 32r with such static vanes can also induce further cavitation within the slurry. The number, shape, and arrangement of rotating high shear elements 32r and/or static vanes can vary. It will be appreciated that the rotating high shear elements 32r, and the static vanes shown only in FIG. 5 are for example purposes only and that other configurations of rotating high shear elements and static vanes are possible and intended to be covered herein.

As best understood by comparing FIGS. 22, 23A, and 23B, the distributor plate 44r in this embodiment is a two-part plate that is mounted to the rotating shaft 34r. The combined distributor plate is bowl shaped and caps the slurry outlet 51r. The distance between the distributor plate 44r and the slurry outlet 51r can be adjusted to restrict the flow of slurry through the slurry outlet 51r. This also controls the back pressure inside the sparger unit 12r. The distributor plate 44r rotates with the high shear element 32r as it rotates on the rotating shaft 34r. The rotating distributor plate 44r allows for a more even dispersion of froth at the top of the slurry contained in the separation tank.

FIGS. 24A and 24B show a variation of the distributor plate 44s in which at least one vane 70s is mounted to the underside of the bowl-shaped distributor plate 44s. Each vane extends radially outwards from the rotating shaft onto which the distributor plate 44s is mounted. The vanes 70s act

like propellers that could draw up the slurry through the sparger unit and would also provide some sparging of bubbles in the slurry.

FIGS. 25A and 25B show a variation of the distributor plate 44t in which at least one vane 70t is mounted to the underside of the bowl-shaped distributor plate 44t. Each vane extends radially outwards in a curve from the rotating shaft onto which the distributor plate 44t is mounted. The vanes 70t act like propellers that could draw up the slurry through the sparger unit and would also provide some sparging of bubbles in the slurry. The angle of the curve of the vanes 70t can be varied according to the particular application.

FIG. 26 shows an embodiment of a sparger unit 12u that is not enclosed with a separation tank in which the sparger unit 12u includes a sparging mechanism 42u for sparging gas into a bubble dispersion within the slurry. A slurry inlet 38u feeds slurry up into the sparger unit 12u. The sparging mechanism 42u is configured such that slurry flow through it is substantially unrestricted. The effective open area in the sparging mechanism 42u is substantially the same as the effective open area in the sparger unit 12u upstream and downstream of the sparging mechanism 42u. This ensures a low pressure drop across the sparging mechanism 42u that allows for a lower pressure and flow rate of slurry through the sparger unit 12u and represents a significant energy savings for the flotation separation system. The pressure drop across the sparging mechanism 42u is about 10 psig or less.

The sparging mechanism 42u comprises a rotating high shear element 32u attached to a rotating shaft 34u that is powered by an electric motor 36u. The slurry may be gravity fed if there is enough hydraulic pressure to ensure that the slurry will flow through the flotation separation system. If the hydraulics of the system requires the slurry to be pumped, the slurry need only be pumped with sufficient pressure to ensure passage of the slurry through the flotation separation system. Nevertheless, the sparger unit 12u will function well over a broad range of slurry flow rates and pressures. Slurry can be introduced into the slurry inlet 38u of the sparger unit 12u at a hydraulic pressure of about 25 psig or less. The sparger unit 12u can operate at a slurry hydraulic pressure of about 2 psig or less. In this embodiment, the slurry inlet 38u is located at the bottom of the sparger unit 12u so that slurry flows upwards through the device as indicated by the arrows in the figure. The sparger unit 12u has a flange with bolt holes 68r that allows the unit to be bolted onto the slurry inlet 38u.

Gas (typically air) is introduced to the sparger unit 12u through gas inlets 40u that are supplied from a gas injection system. In this embodiment, the air is injected down the rotating shaft 34u. Air enters through a sealed bearing housing (not shown) at the top of the rotating shaft 34u and travels through the rotating shaft 34u and exits from the gas inlets 40u into the sparger unit 12u. The passing slurry flow immediately shears the gas to form bubbles as the gas enters the sparger unit 12u through the gas inlets 40u. The gas need not be at a high pressure for effective bubble formation in the slurry. Even at high slurry feed rates, the gas flow and pressure needs only be high enough to allow bubble formation in the slurry.

The bubbles are sheared into smaller bubbles as the slurry passes through the sparging mechanism 42u and forms a fine bubble dispersion within the slurry. The formation of the bubble dispersion within the sparger unit 12u exposes a larger volume of slurry to the surface of the bubbles. This increases the incidences of hydrophobic species collision

21

with the bubbles and increases the probability of adhesion of a hydrophobic species to a bubble. In the embodiment depicted in FIG. 26, this gas shearing is aided with the rotating high shear element 32u. The rotating high shear element 32u is intended to shear gas bubbles only and is not intended to agitate or mix the entire slurry volume, therefore, the electric motor 36u need only be large enough to drive the rotating high shear element 32u. This represents a significant energy savings over flotation separation systems that require agitation of the slurry for bubble shearing.

In addition, the rotating high shear elements 32u could have openings as depicted in FIG. 26. These openings create additional shear which assists in bubble formation. The blades of the rotating high shear elements 32u could also be 15 partially inclined to help push the slurry through the system. The rotating high shear elements 32u induce low-pressure zones behind the rotating blades to induce cavitation. The blades can be configured and operated in such a way that the environment within the sparger unit 12u supports and 20 induces cavitation within the slurry.

The creation of the bubble dispersion with the sparger unit 12u exposes the entire volume of slurry to the surface of a bubble. Therefore, the bulk of the adhesion of a hydrophobic species to a bubble is likely to occur within the sparger 25 assembly 30u, in and downstream of the sparging mechanism 42u. Once the slurry has passed though sparging mechanism 42u, the slurry and the bubble dispersion is discharged through a slurry outlet 51u as shown by the arrows in the figure. In some variations of the sparger unit 12u could also incorporate static vanes as shown for example in FIG. 5 to increase the shearing of gas bubbles in the sparging mechanism. The combination of fixed vanes against the rotating vanes creates additional shear for bubble dispersion. The interaction of the rotating high shear elements 32u with such static vanes can also induce further cavitation within the slurry. This invention has been described with reference to several preferred embodiments. Many modifications and alterations will occur to others upon reading and understanding the preceding specification. It is intended that the invention be construed as including all such alterations and modifications in so far as they come within the scope of the appended claims or the equivalents of these claims.

The invention claimed is:

1. A flotation separation system for partitioning a slurry, the slurry including a hydrophobic species that can adhere to gas bubbles formed in the slurry, said flotation separation system comprises:

a flotation separation cell that comprises a sparger unit and a separation tank;

said sparger unit comprises:

a slurry inlet located at a first portion of a sparging mechanism, said slurry inlet for receiving a slurry; a gas inlet located at said first portion of said sparging mechanism, said gas inlet for introducing a gas into the slurry, the gas having enough pressure to introduce the gas into the slurry;

said sparging mechanism for dispersing the gas bubbles within the slurry, the effective open area in said sparging mechanism is substantially the same as the effective open area in said sparger unit both upstream and downstream from said sparging mechanism, said sparging mechanism is constructed such that the slurry flows through said sparging mechanism in a substantially unrestricted manner, the pressure

22

across said sparging mechanism during the operation of said flotation separation system is about 10 psig or less;

a high shear element located within said sparging mechanism between said first portion and a second portion of said sparging mechanism, said high shear element for shearing the gas into a bubble dispersion within the slurry for adhesion of the hydrophobic species to the bubbles dispersion within said sparger unit;

wherein said high shear element comprises a rotating shaft and a rotating high shear element mounted to said rotating shaft;

a slurry outlet located at said second portion of said sparging mechanism, said slurry outlet for discharging the slurry containing the bubble dispersion into said separation tank;

an adjustable distributor plate at said slurry outlet, said distributor plate for restricting the flow of slurry through said slurry outlet; and

said distributor plate mounted to said rotating shaft and rotating with said high shear element; and

said separation tank constructed to allow the recovery of the bubble dispersion from said separation tank.

2. The flotation separation system of claim 1 in which said distributor plate is bowl shaped.

3. The flotation separation system of claim 1 in which said distributor plate further comprises at least one vane that extends radially outwards.

4. The flotation separation system of claim 1 in which said distributor plate further comprises at least one vane that extends radially outwards and said at least one vane is curved.

5. The flotation separation system of claim 1 wherein said high shear element comprises a plurality of rotating high shear elements in series.

6. The flotation separation system of claim 1 wherein said high shear element comprises a rotating high shear element and a static high shear element.

7. The flotation separation system of claim 1 wherein said sparger unit is surrounded by a center well.

8. The flotation separation system of claim 1 wherein said 45 rotating high shear element comprises blades with openings to create additional shear within said sparger mechanism.

9. The flotation separation system of claim 1 wherein said rotating high shear element comprises blades that are inclined to push slurry through the sparger mechanism.

10. The flotation separation system of claim 1 in which said separation tank is either open to atmosphere or closed at a pressure other than atmospheric.

11. The flotation separation system of claim 1 in which said gas inlet is located on said rotating shaft.

12. The flotation separation system of claim 1 in which said distributor plate also controls the pressure within said sparger system.

13. The flotation separation system of claim 1 wherein the pressure drop across said sparging mechanism during the operation of said flotation separation system is about 1 psig or less.

14. The flotation separation system of claim 1 wherein the slurry is introduced to said sparger unit at a hydraulic pressure of about 25 psig or less.

15. The flotation separation system of claim 1 wherein the slurry is introduced to said sparger unit at a hydraulic pressure of about 2 psig or less.

23

16. The flotation separation system of claim 1 wherein the slurry is introduced to said sparger unit at a hydraulic pressure determined by gravity flow or pressure.

17. The flotation separation system of claim 1 wherein said first portion of said sparging mechanism is located above said second portion of said sparging mechanism.

18. The flotation separation system of claim 1 wherein said first portion of said sparging mechanism is located below said second portion of said sparging mechanism.

19. The flotation separation system of claim 1 wherein said flotation separation cell comprises an overflow launder constructed to capture froth overflow from said separation tank.

20. The flotation separation system of claim 1 wherein said flotation separation cell comprises an underflow removal port, said underflow removal port is a drain, a pump, sand gates, or an overflow weir system.

21. The flotation separation system of claim 1 wherein said flotation separation cell comprises a froth washing system for washing the froth in said separation tank, said froth washing system is a perforated wash pan, perforated pipes, height-adjustable perforated pipes, or a underwash system.

22. The flotation separation system of claim 1 wherein said gas inlet receives gas from a gas compressor, a compressed gas tank, an educator, an aspirator, or a gas blower.

23. The flotation separation system of claim 1 wherein said flotation separation cell comprises a plurality of sparger units for introducing slurry at multiple locations within said separation tank.

24. The flotation separation system of claim 1 wherein said flotation separation cell comprises:

a plurality of sparger units for introducing slurry at multiple locations within said separation tank; and a feed manifold distributor for distributing slurry to each said sparger unit.

25. The flotation separation system of claim 1 in which each said flotation separation cell comprises multiple said sparger units.

26. The flotation separation system of claim 1 in which said sparger unit is located within said separation tank.

27. The flotation separation system of claim 1 in which said sparger unit is located external to said separation tank.

28. A sparger unit for forming bubbles in a slurry in a flotation separation system the slurry including a hydrophobic species that can adhere to gas bubbles formed in the slurry, said sparger unit comprises:

a slurry inlet located at a first portion of a sparging mechanism, said slurry inlet for receiving a slurry; a gas inlet located at said first portion of said sparging mechanism, said gas inlet for receiving a gas, the gas having enough pressure to introduce the gas into the slurry;

said sparging mechanism for dispersing the gas bubbles within the slurry, the effective open area in said sparging mechanism is substantially the same as the effective open area in said sparger unit both upstream and downstream from said sparging mechanism, said sparging mechanism is constructed such that the slurry flows through the effective open area in said sparging mechanism in a substantially unrestricted manner, the pressure across said sparging mechanism during the operation of said sparger unit is about 10 psig or less;

24

a high shear element located within said sparging mechanism between said first portion and a second portion of said sparging mechanism, said high shear element for shearing the gas into a bubble dispersion within the slurry for adhesion of the hydrophobic species to the bubble dispersion within said sparger unit;

wherein said high shear element comprises a rotating shaft and a rotating high shear element mounted to said rotating shaft;

a slurry outlet located at said second portion of said sparging mechanism, said slurry outlet for discharging the slurry containing the bubble dispersion from said sparger unit;

an adjustable distributor plate at said slurry outlet, said distributor plate for restricting the flow of slurry through said slurry outlet; and

said distributor plate mounted to said rotating shaft and rotating with said high shear element.

29. The sparger unit of claim 28 in which said distributor plate is bowl shaped.

30. The sparger unit of claim 28 in which said distributor plate further comprises at least one vane that extends radially outwards.

31. The sparger unit of claim 28 in which said distributor plate further comprises at least one vane that extends radially outwards and said at least one vane is curved.

32. The sparger unit of claim 28 wherein said high shear element comprises a plurality of rotating high shear elements in series.

33. The sparger unit of claim 28 wherein said high shear element comprises a rotating high shear element and a static high shear element.

34. The sparger unit of claim 28 wherein the pressure across said sparging mechanism during the operation of said sparger unit is about 1 psig or less.

35. The sparger unit of claim 28 wherein the slurry is introduced to said sparger unit at a hydraulic pressure of about 25 psig or less.

36. The sparger unit of claim 28 wherein the slurry is introduced to said sparger unit at a hydraulic pressure of about 2 psig or less.

37. The sparger unit of claim 28 wherein the slurry is introduced to said sparger unit at a hydraulic pressure determined by gravity flow or pressure.

38. The sparger unit of claim 28 wherein said first portion of said sparging mechanism is located above said second portion of said sparging mechanism.

39. The sparger unit of claim 28 wherein said first portion of said sparging mechanism is located below said second portion of said sparging mechanism.

40. The sparger unit of claim 28 wherein said gas inlet receives gas from a gas compressor, a compressed gas tank, an educator, an aspirator, or a gas blower.

41. The sparger unit of claim 28 wherein said sparger unit is surrounded by a center well.

42. The sparger unit of claim 28 wherein said rotating high shear element comprises blades with openings to create additional shear within said sparger mechanism.

43. The sparger unit of claim 28 wherein said rotating high shear element comprises blades that are inclined to push slurry through the sparger mechanism.

44. The sparger unit of claim 28 in which said gas inlet is located on said rotating shaft.
